UNITED STATES PATENT OFFICE.

SONIA SALKIND, OF LONDON, ENGLAND, ASSIGNOR TO HARVEY NICHOLS AND COMPANY LIMITED, OF LONDON, ENGLAND, A CORPORATION OF GREAT BRITAIN.

WOMAN'S UNDERGARMENT.

Application filed March 25, 1927, Serial No. 178,281, and in Great Britain March 27, 1926.

This invention relates to women's combination undergarments, and has for object to produce a reducing effect on the diaphragm, the abdomen and posterior while at the same time conducing to the comfort of the wearer and imparting elegance to the figure. The garment is, therefore, particularly suitable for full figures although, obviously, it cannot but be also appropriate for wear by slim 10 women and girls.

According to this invention, the garment, comprising in combination a brassière and camisole with shoulder-straps, is furnished in front with an inner diaphragm-supporting part or apron secured at the top to the upper part of the camisole-portion or camisole, tapering downwards and provided at its lower end with stocking-suspenders and a posterior-supporting and reducing part 20 formed at the back also provided with stocking-suspenders. Or the posterior-supporting part consists of a rear inner depending apron secured at the back to the top of the camisole or brassière, gradually increasing 25 in width downwards and provided at each lower corner with an elastic band having a stocking-suspender. If desired one end of an elastic band is connected to each lower corner of the rear depending part, the stocking-suspender is slideable thereon and the other end of the elastic band is secured to the bottom of the camisole portion at the side. The front and back portions of the brassière or the upper part of the camisole 35 or both is or are suitably divided at each side and the said portions are connected together by a short piece or straps of elastic material. The front supporting part or apron is conveniently made in the shape of 40 an inverted truncated cone with the base attached by sewing to the inside of the top of the camisole-portion and the upper ends of a pair of stocking-suspenders are stitched or buttoned to the lower and narrow part 45 near together and side by side. The rear reducing part or apron is also suitably made in the shape of a truncated cone with a base of part circular shape and is sewn at the top to the inside of the top of the camisole-portion. Or the rear inner depending posterior-supporting and reducing part or 50 apron may be dispensed with and the elastic stocking suspenders are secured to the camisole-portion at the sides, the camisole being 55 so shaped that it then takes the place and

performs the function of the said rear inner depending part. The knickers or knicker-portions are preferably cut full to allow plenty of freedom for the movement of the legs and may be slit at the sides or provided 60 with a tab between the legs stitched to the back and detachably connected to the front by press-button fastening or the like. Being cut full the knickers may also enable the wearer to dispense with an under slip 65 or petticoat. On the other hand a short skirt may be substituted for the knickers or the garment may be made without either knickers or skirt but in that case the camisole-portion is suitably made somewhat 70 longer.

And in order that the invention may be readily understood and carried into effect, reference will be made to the accompanying drawings, in which:—

Figure 1 is a perspective view of one construction of garment broken away in parts in front to clearly show the construction of the diaphragm supporting part.

Figure 2 is a somewhat similar view taken more from the side than Figure 1 and broken away in parts at the back to show the construction of the posterior reducing part and

Figure 3 is a view of the garment turned inside out to show still more clearly the shape and construction of the posterior reducing part and one method of connecting the stocking suspenders thereto.

Figure 4 is a perspective view of the lower part of a garment showing another method 80 of connecting stocking suspenders thereto.

Figure 5 is a sectional side elevation of a modified construction of garment in which the back of the camisole forms the posterior-reducing part.

Figure 6 is a perspective view of a garment provided with a short skirt and Figure 7 is a similar view of a garment having neither knickers nor skirt.

According to the construction illustrated by Figures 1, 2 and 3, the garment is suitably 81 inches round the bust and 36 inches round the hips with an upper or brassière-portion *a* of lace, 2 inches in depth, reinforced at the upper edge and provided with shoulder-straps *b*, the combined brassière *a* and camisole-portion *c* is 16 inches in depth and the knickers-portion *d* is about 38 inches round and 8 inches deep with a lace edging of, say, 4 inches. The upper parts, consist- 100 105 110

ing of the combined brassière *a* and a camisole *c*, which moulds the figure softly, is of porous silk tricot and small elastic bands *e* under the armpits assist the material to yield with every movement of the body. The knickers *d*, suitably made of silk or crêpe de chine, are cut full and part circular or curved both in front and behind, being slightly deeper in the middle than at the 10 sides and a flounce or edging *f* of scalloped lace $3\frac{1}{2}$ to 4 inches wide is somewhat gathered at the upwardly curved sides and continues up to the tops of the slits formed by the upward curved parts *g* which terminate 15 at the bottom of the camisole portion but which are covered by the overlapping parts of the lace flounce at that place. The front diaphragm supporting part or apron *h* and the back supporting part or apron *i* are also 20 suitably made of porous silk tricot, and both are connected at the top to the camisole portion *c*. The front supporting part *h* is 10 inches wide at the top and there connected by sewing to the camisole portion *c*, it is 4 25 inches wide at the bottom with a depth or length of about 10 inches and two elastic stocking-suspenders *k* are stitched side by side to the bottom of the said front supporting part. The stocking suspenders *k*, being then engaged with the stocking inside the legs, exert and pull on the front diaphragm supporting or apron-part *h* and tend to gently compress the diaphragm and the stocking suspenders similarly engage the 30 abdomen. At the back of the knickers *d* is sewn the usual connecting tab *l*, $1\frac{3}{4}$ inches wide and 6 inches long, furnished at its free end with two or three press-buttons, and the knickers are provided in front with a similar 35 number of corresponding press-button fastenings sewn on to a piece of fabric stitched to the knickers. This arrangement of detachable connection is well known and is only partly shown in Figure 3 so as not to complicate the other drawings. Or the tab may 40 be permanently joined in known manner at both ends to the knickers, if desired, as the knickers are cut full and slit at the sides. The rear reducing part *i* is about $5\frac{1}{2}$ inches 45 wide at the top, 12 inches wide at the bottom and about 16 inches from top to bottom so as to extend well down to the bottom of the spine and over the posterior. The sides may be straight or slightly curved inwards. The bottom or base of the rear reducing part or apron *i* is, moreover, cut hollow or curved inwards and each lower corner, where one end of an elastic suspender band or strap *m* is attached, may, if desired, 50 be cut off square at *n* as shown in Figures 2 and 3. These suspender-straps *m* are conveniently about 10 inches long and each free end of a strap, after passing it through the loop or ring *o* of a stocking suspender, is 55 permanently connected at *p* to the lower

edge at a side of the camisole-part *c* so that the suspender hangs in a loop and each suspender connected to the outside of a stocking-leg, adjusts itself to the bottom of its loop and exerts a gentle pull on its lower 70 corner of the rear reducing part or apron *i* and so exerts a certain amount of compression on the posterior.

This garment may be slipped on over the ordinary corset and while being extremely 75 comfortable, gives an unbroken and graceful line to the frock or gown in front and at the back even to a full figure. For slim women and girls, in some circumstances, it will prove to be sufficient underwear or may 80 be worn for example over a chemise-vest of woven silk or woollen gauze.

The construction shown in Figure 4, is very similar to that just described, the only difference being that the rear suspender 85 straps *m'* are connected only to the lower outer ends at *n* to the rear reducing part *i*. The camisole-portion *c* may also be provided with stocking-suspenders *q* connected thereto at *p*.

On referring to Figure 5, it will be seen that the rear inner depending reducing part or apron *i* is dispensed with. As in the previous instances, the brassière *a* with shoulder-straps *b* is connected to the top 95 of the camisole portion *c* and is furnished at each side with elastic bands or insertion *e*. The camisole portion *c* has secured thereto in front and at the top the inner downwardly tapering diaphragm-supporting part or 100 apron *h* and the knickers *d* are connected to the lower edge of the camisole-portion *c*. The inner diaphragm-supporting part *h* is provided with stocking suspenders *k* and the camisole-portion *c* has sewn or otherwise 105 connected thereto, at the sides and towards the rear, the stocking suspenders *m*² which, together with the back of the camisole portion have the effect of supporting and reducing the posterior.

The modification shown in Figure 6 illustrates a garment made very similar to that shown in Figure 5, that is, the camisole portion is provided with stocking suspenders *m*², the front inner depending diaphragm- 115 and abdomen-supporting portion *h* is furnished with stocking suspenders *k* and the separate rear inner depending posterior-supporting and reducing part is dispensed with. In this case, however, the knickers 120 are dispensed with and a short skirt *s* is substituted therefor.

Finally, on referring to Figure 7, it will be seen that both knickers and skirt are dispensed with, the camisole-portion *c'* is trimmed with a flounce or edging of lace *f'*, and is provided with short stocking suspenders *m*³ at the sides. The front inner depending part *h* is shaped as before described and is furnished with stocking suspenders *k*. If de- 130

sired, this garment may also be provided with a rear inner depending posterior reducing part or a rron such as marked *i* with suspenders *m* as in Figures 1, 2 and 3 or as shown in Figure 4.

For a full figure, the front inner depending part *h* is generally made wider, as shown, and if there be a rear inner depending part such as is shown at *i* in Figures 1, 2 and 3, 10 for example, this may also be wider and particularly so at the bottom according to the wearer's figure.

The camisole-portion of these garments may be made for example, of mercerized 15 cellular cotton, washable net, tulle tricot, or other suitable material. The depending front and/or rear supporting portions are suitably made of the same kind of material and of single or double thickness and the 20 knickers—or skirt—portion is conveniently made of silk or any other suitable material.

I claim:—

1. A combination undergarment comprising an upper portion consisting of a brassière and a bodice, shoulder straps secured to the top of said upper portion, a downwardly tapering diaphragm supporting part located inside of, secured to and depending from the top of the upper portion, stocking 25 suspenders secured to the lower edge of the said diaphragm supporting part, a posterior supporting and reducing part formed at the back of the garment and stocking suspenders secured to the lower part thereof.

2. A combination undergarment comprising an upper portion consisting of a brassière and a bodice, shoulder straps secured to the top of said upper portion, a nether garment portion, a downwardly tapering 30 diaphragm supporting part secured to and depending from the top of the upper portion and located inside thereof, stocking suspenders secured to the lower edge of the said diaphragm supporting part, a posterior supporting and reducing part secured at the top to the top of the back of the upper portion, and stocking suspenders secured to the lower corners of the said posterior supporting part and to the lower edge of said upper portion.

3. A combination undergarment comprising an upper portion consisting of a brassière and a bodice, shoulder straps secured to the top of said upper portion, a nether garment portion, a downwardly tapering 35 diaphragm supporting part secured to and depending from the top of the upper portion and located inside thereof, stocking suspenders secured to the lower edge of the said diaphragm supporting part, a depending posterior supporting and reducing part, increasing in width downwards and secured at the back to the top of the said upper portion, and stocking suspenders secured to the lower

corners of the said posterior supporting part.

4. A combination undergarment comprising an upper portion consisting of a brassière and a bodice, shoulder straps secured to the top of the said upper portion, a nether garment portion, a downwardly tapering 40 diaphragm supporting part located inside the garment secured to and depending from the top of the upper portion, stocking suspenders secured to the lower edge of the said diaphragm supporting part, a depending posterior supporting and reducing part located within the garment, increasing in width downwards, inwardly curved at the bottom and secured at the back to the top of the bodice portion, and stocking suspenders 45 secured to the lower corners of the posterior supporting and reducing part.

5. A combination undergarment comprising an upper portion consisting of a brassière and a bodice, shoulder straps secured to the top of said upper portion, a nether garment portion, a downwardly tapering diaphragm supporting part located inside the garment, secured to and depending from the top of the said upper portion, stocking 50 suspenders secured to the lower edge of the said diaphragm supporting part, a depending posterior supporting and reducing part located within the garment, increasing in width downwards, inwardly curved at the bottom and secured at the back to the top of the said upper portion, straps secured at one end to the posterior supporting part and at the other end and at the side to the lower edge of the upper portion of the garment 55 and stocking suspenders, each slidale on a strap.

6. A combination undergarment comprising an upper brassière portion, divided at each side to form front and rear portions, and a bodice, elastic straps connecting the front and rear portions of said upper portion, shoulder straps secured to the top of said upper portion, a nether garment portion, a downwardly tapering diaphragm 60 supporting part located inside the garment, secured to and depending from the top of the said upper portion, stocking suspenders secured to the lower part of the said diaphragm supporting part, depending posterior-supporting and reducing part located within the garment increasing in width downwards, inwardly curved at the bottom and secured at the back to the top of the said upper portion, straps secured at one end to the lower corners of the posterior supporting part and at the other end at the side to the lower edge of the upper portion of the garment and stocking suspenders each slidale on a strap.

SONIA SALKIND.
